FOREIGN PATENT DOCUMENTS

JP 2000-134839 A 5/2000

Primary Examiner — Susan Bennett Hattan*Assistant Examiner* — Brett Miller(74) *Attorney, Agent, or Firm* — Pearne & Gordon LLP(57) **CLAIM**

The ornamental design for a rotor for rotary electrical machine, as shown and described.

DESCRIPTION

FIG. 1 is a perspective view of a rotor for rotary electrical machine showing our new design;

FIG. 2 is a front view thereof, a bottom view and a plan view being identical thereto;

FIG. 3 is a rear view thereof;

FIG. 4 is a right side view thereof;

FIG. 5 is a left side view thereof; and,

FIG. 6 is a cross-section view thereof taken along the line 6-6 of FIG. 4.
